(57) CLAIM

The ornamental design for a mug press, as shown and described.

DESCRIPTION

FIG. 1 is a top perspective view in a closed configuration with a mug shown in phantom showing my new design;

FIG. 2 is a top view with a mug shown in phantom thereof;

FIG. 3 is a bottom view thereof;

FIG. 4 is a rear view with a mug shown in phantom thereof;

FIG. 5 is a front view with a mug shown in phantom thereof;

FIG. 6 is a left side view with a mug shown in phantom thereof;

FIG. 7 is a right side view with a mug shown in phantom thereof; and,

FIG. 8 is a top perspective view in an open configuration. The broken line showing of the mug is included for the purpose of illustrating environment and forms no part of the claimed design.
